UNITED STATES PATENT OFFICE.

FRANK R. SPECK, OF PHOENIX, ARIZONA.

SAND PICTURE AND PROCESS OF MAKING IT.

Application filed January 19, 1928. Serial No. 247,959.

This invention relates to pictures made by sifting sand upon a glass plate, and particularly to a method of making such pictures.

The general object of the invention is to provide a method of making pictures from grains of sand which is such that the artist can follow a sketch in making the picture from said grains and can from time to time determine whether or not the sand grain picture is correct and in accordance with his ideas.

My invention is illustrated in the accompanying drawing, wherein:

Figure 1 is a front view of a sand picture constructed in accordance with my process;

Figure 2 is a top plan view of the sketch from which the sand picture is made;

Figure 3 is a vertical sectional view showing the process of making the sand picture;

Figure 4 is a like view to Figure 3 but showing the sand picture being checked up by viewing the picture in a mirror;

Figure 5 is a vertical sectional view of the completed picture.

In the production of the sand grain picture, a frame 10 is used which is rectangular in form and may be made of tin, glass, metal or any other suitable material but this frame is shown as being of metal and as having the relatively narrow facing flanges 11 and the outwardly extending, relatively deep flanges 12. In the production of a picture, a sheet of glass 13 is disposed within the frame and bearing against the flanges 10. Of course, it will be understood that the frame and the glass 13 might be integral or made of one integral piece of glass.

In the production of the picture, a sketch 14 is used, as shown in Figure 2, and the frame laid over this sketch, the sketch showing through the glass 13 (Fig. 3). The artist then takes sand of different colors by means of a small spoon and distributes it on the glass plate 13 in accordance with the sketch, flat pointed steel instruments being used to move the grains of sand about from place to place until the properly colored grains of sand have been disposed in the correct positions. A mirror 15 is disposed beside the frame 10 and as the picture progresses the artist from time to time lifts the frame up with the glass and the sand thereon and holds the partially completed picture over the mirror (see Fig. 4) to observe the work from the under side, that is from the

side from which it will be observed when the work is completed.

After the sand is all put in place so that a complete picture is reflected from the mirror, more sand is carefully sifted on the back, making the entire depth of the sand perhaps $\frac{1}{6}$ ", it being understood that the sand grains are very fine and almost in powdered condition. Next a piece of felt 16, which is the size of the frame, is saturated with soda silicate or other glue or cement and carefully placed over the last named layer of sand. Over this felt is placed a heavy sheet of tin or sheet metal 17 and the edges of the frame, that is the flanges 12, are pressed over against this sheet of metal. The whole is then put under pressure and the picture is ready to be turned over. It will be noted that the sketch 14 is reverse to the complete picture shown in Figure 1. The completed picture is now ready for a finished metal or wooden frame and for the market.

I am aware of the fact that sand pictures have heretofore been made but these have been made by sticking the sand upon the glass with glue, cement or other like material. No glue or other cementitious material is used with the sand pictures made as described, but by making the sand pictures as stated it is possible to hold the sand so firmly against the glass that it is impossible for the sand to shift or for different colored sands to mix with each other. Thus the outlines of the picture are perfectly well defined and the different colors clearly and permanently separated. Grains of sand of different sizes may, of course, be used so that the proper perspective effect may be secured. This sand is such as is found in the Painted Desert and the pictures illustrate scenes in the Painted Desert, such, for instance, as the Rainbow Natural Bridge north of the Arizona-Utah line, this being the scene illustrated in the drawing. Obviously other pictures may be made in the same manner.

While I have heretofore referred to and preferably use a sketch, as in Figure 2 at 14, it is to be understood that any pattern may be used to indicate the proper positioning of the sand and a stencil, for instance, is a pattern which could be used in forming the picture. Thus, for instance, one stencil could be used to indicate the bridge, another stencil to indicate the sand forming the top of the bridge, another stencil for the background, etc. Fur-

thermore, I do not wish to be limited to the use of an adhesive-coated fibrous pad as, for instance, the felt layer 16, as under some circumstances the adhesive may be left off and a 5 pad of fibrous material such as blotting paper, felt or the like used. The soft and fibrous nature of such a pad causes the grains to be embedded in the pad to a considerable extent so that the grains will not shift after they have 10 been submitted to pressure and the backing put in place.

I claim:—

1. The method of making a sand picture which consists in disposing a frame having a 15 glass front over a sketch of the scene to be depicted, disposing different colored sands upon the back face of the glass, placing a textile backing having an adhesive-coated surface over the sand after the picture is completed, and then putting a backing plate upon the textile fabric and engaging it with the frame.

2. The method of making a sand picture which consists in disposing a frame having a 25 glass front over a sketch, arranging grains of different colored sands upon the inside surface of the glass plate, sifting sand over the inner surface of the completed picture until the entire inner surface of the completed picture is covered, placing a pad of soft, fibrous, 30 material having its inner surface covered with adhesive over the layer of sand, disposing a metal plate over the textile fabric, and engaging the metal plate firmly with the frame.

3. As an article of manufacture, a sand picture comprising a frame having a glass front, the inner face of the glass having a thin layer of colored sands arranged thereon to form the picture, a second layer of sand disposed upon the first layer, a pad of soft, 35 fibrous material, having adhesive applied to its inner face, the pad being disposed over the second layer of sand, and a metal plate dis-

posed against the pad and engaged firmly with said frame.

4. As an article of manufacture, a sand picture comprising a frame having a glass front, the inner face of the glass having a thin layer of colored sands arranged thereon to form the picture, a second layer of sand disposed upon the first layer, a pad of soft, fibrous material having adhesive applied to its inner face, the pad being disposed over the second layer of sand, and a metal plate disposed against the fibrous pad, the metal frame being turned inward against the metal plate to hold it in place.

5. A method of making a sand picture which consists in disposing different colored sands upon the back face of a piece of glass 60 disposed within a frame, the sands being disposed in accordance with a pattern, placing a pad of fibrous material over the sand after the picture is completed, and then putting a backing plate upon the pad and engaging the 65 backing plate with the frame.

6. A method of making a sand picture which consists in disposing different colored sands upon the back face of a sheet of glass disposed in a frame having outstanding 70 flanges, placing a pad of fibrous material over the sand after the picture is completed, putting a backing plate upon the pad, and bending the flanges of the frame over upon the back plate.

7. As an article of manufacture, a sand picture comprising a frame having a glass front, the inner face of the glass having thereon a thin layer made up of colored sands arranged thereon to form a picture, a pad of relatively 80 soft fibrous material applied to the inner face of the sand, and a metal plate disposed against the plate and engaged firmly with said frame.

In testimony whereof I hereunto affix my signature.

FRANK R. SPECK.
